G. A. BLUE

GRAVE MARKER

Filed Sept. 8, 1925

Robt. Robt. Hill
Attorney

UNITED STATES PATENT OFFICE.

GLENN A. BLUE, OF TWIN FALLS, IDAHO.

GRAVE MARKER.

Application filed September 8, 1925. Serial No. 55,005.

This invention relates to a grave marker, and particularly to a construction involving a supporting stake or member carrying a memorial tablet or name plate.

5 In previous constructions of this character it has been usual to provide in the memorial tablet a space to receive a card or other data concerning the deceased, and this construction has been found very impractical because of the fading and deterioration of such an inserted card, so that my invention contemplates the use of a permanent marking plate having the indicia die-stamped thereon so as to be impervious to 10 weather conditions and always readily visible to the observer.

In other constructions it has also been the practice to assemble the marking plate and stake before the driving of the latter in its 20 proper position to indicate the grave to be marked. This often defeated the securing of the stake in hard or rocky ground as it was not provided with suitable means by which a tool could be applied for driving 25 purposes. I have therefore devised a construction in which the stake is separable from the marking plate and provided with means for driving the same and also with anchoring devices to prevent its withdrawal 30 or displacement.

The marking plate is further formed with means to interlock with the upper end of the stake which is so inclined at an angle to the vertical as to dispose the plate in a 35 position to be easily read by the observer on looking downward. In the ordinary construction of such plates they are disposed in the same vertical plane as the stake and it is necessary to bend down in order to 40 read the indicia inscribed thereon.

In the use of a plate to be die stamped it becomes important to separate the plate member from the other elements of the supporting back and stake in order to properly 45 perform the stamping operation, and the structure presented permits the plate member to be entirely detached and subsequently applied to the supporting back and interlocked with the stake.

50 The invention has for an object to provide a novel and improved construction comprising a stake member and a marking

plate or tablet provided with means to embrace the upper end of the stake member and for interlocking therewith.

A further object of the invention is to provide an improved form of stake having an interlocking connection at its upper end for the marking plate and also a driving shoulder together with anchoring means 60 adapted to secure the stake in position when driven.

Another object of the invention is to provide a construction embodying a sheet metal marking plate adapted to receive die 65 stamped indicia and supported by a backing member interlocked with an angularly disposed extension from a supporting stake.

Other and further objects and advantages of the invention will be hereinafter set forth 70 and the novel features thereof defined by the appended claims.

In the drawing:

Figure 1 is a perspective of the invention;

Figure 2 is a horizontal section through the upper portion of Figure 1;

Figure 3 is a detail perspective of the stake;

Figure 4 is a central vertical section 80 through Figure 1;

Figure 5 is a similar view of a modified form of the invention; and

Figure 6 is a section on the line 6—6 of 85 Figure 5.

Like reference numerals designate corresponding parts throughout the several figures of the drawing.

While the invention has been described as a grave marker, it will be understood that 90 the marking plate may be used for any desired purpose and its particular application as a memorial tablet is herein shown and described. In this form of the invention the numeral 10 designates the stake which is of partially resilient material and has at its upper end an angularly disposed portion 11 of substantially wedge-shape provided with an interlocking projection 12. The portion 11 is formed intermediate its edges with a 95 driving lug 13 adapted to cooperate with a suitable driving tool for the purpose of forcing the stake into the earth. This lug may also be utilized to carry indicia designating 100

the lot or grave number, as shown at 14 in Figure 1. The lower portion of the stake may be provided with outwardly bent spurs or anchors 15 formed from the body thereof and adapted to be forced inwards in the driving operation but to exert an outward friction against any effort to withdraw the stake from its driven position.

Cooperating with the head 11 of the stake 10 is the marking plate or tablet 16 which has a substantially plane body portion 17 to receive the indicia relating to the purpose of the marker. For instance, when used for grave designating purposes, a portion of 15 this data may be preliminarily die stamped upon the plate and the name of the deceased and age and date of death later inserted, or if preferred the complete information may be die stamped at a single operation, the 20 plate being at that time removed from the stake and adapted to be applied to a proper supporting base for that purpose. The plate 16 is formed with a depending flange 18 about its edges and the flange adjacent the 25 stake is formed with a projecting body 19 having bendable ears 20 adapted to be folded into engagement with the angular portion 11 of the stake. Such engagement with the wedge shaped portion would substantially 30 retain the plate in position but this may be further secured by the use of rivets or bolts 21 passing through the ears 20 and apertures 22 in the head 11 of the stake.

Cooperating with the name plate a back 35 plate 23 is provided which is formed with a circumferential up-turned edge 24 passing within the flange 18 from the name plate. The lower flange 24 is formed with an aperture 25 adapted to receive the interlocking 40 projection 12 carried by the head of the stake.

In assembling the construction shown in Figures 1 to 4 the flange 18 of the name plate extends over the cooperating flange 24 of 45 the back plate as shown in Figure 4 and the lower portion of this back plate receives the interlocking extension from the stake. The extension 19 from the name plate is then brought into contact with the wedge shaped 50 head of the stake and the ears 20 folded into position beneath the same so as to embrace and interlock the stake and plate thus permitting the use of an all-metal name plate of sufficiently light material to be conveniently die stamped and its application to 55 the stake after the latter has been driven to proper position.

In Figures 5 and 6 a modified form of the invention is shown in which the name plate 60 26 is mounted upon a stake member 27 by a slightly different form of interlocked connection. This member 27 is formed with the driving lug 28 and the angularly disposed extension 29 which forms a brace extending 65 behind the entire body of the name plate

which carries the die stamping 30 similar to that shown in Figure 1. The back plate 31 is formed at one end with an inturned flange 32 having a rebent free end 33 apertured to receive the upper end of the interlocking extension 29 from the stake while the opposite end of the back plate is flanged inwardly at 34 and rebent at 35, both of these members being apertured to permit the passage of the stake extension 29 therethrough. This extension is formed at its lower portion with locking spurs 36 of resilient material preferably formed from the body of the extension and adapted to be compressed when the extension is inserted between the plates and to later expand and lock it in position as shown in Figure 6. The marking plate is provided with a peripheral flange, one side 37 thereof being extended to partially embrace the flange 32 of the back and form an interlocked connection for the plate 26 and the opposite side flange 38 of this plate is apertured to permit the passage of the extension 29 therethrough. By this means the plate is positively interlocked with the back 90 and both of these members rigidly supported upon the extension from the stake.

The invention presents a grave marker of durable metallic material in which the inscription is clearly legible under all conditions and practically permanent so as to be conveniently read. The construction by which the main plate and stake may be assembled after the driving of the latter provide for a proper securing of the stake and also the convenient manipulation of the plate for the production of the die stamp indicia thereon. This separable construction also forms an important factor in the packing, storage and shipping of the article.

While the specific construction of the several parts has been shown and described, it will be obvious that changes and alterations may be made therein without departing from the spirit of the invention as defined by the appended claims.

Having thus described my invention, what I claim as new and desire to secure by Letters Patent is:

1. In a marker, a stake member provided with a laterally enlarged head having interlocking means, and a marking plate formed with bendable members adapted to embrace and interlock with said head.

2. In a marker, a stake member provided at its upper end with a head and interlocking projection, a marking plate having at its base an extension adapted to enclose said head, and a back plate apertured to receive said projection.

3. In a marker, a stake member provided at its upper end with a laterally disposed head, a marking plate having at its base an extension adapted to embrace said head, and support the plate in an inclined position and

a driving lug upon said stake having a horizontal face disposed at the head portion thereof.

4. In a marker, a stake having an enlarged angularly disposed head portion, a back plate adapted to interlock with an extension from said portion, and a name plate mounted upon said back plate and provided with means to embrace said stake head.
5. In a marker, a stake having an enlarged

angularly disposed head portion, a back plate adapted to interlock with an extension from said portion, a name plate mounted upon said back plate and provided with means to embrace said stake head, and securing devices extending through said embracing means and apertures in the stake head. 15

In testimony whereof I affix my signature.

GLENN A. BLUE.
